STRIP FEEDING MACHINE HAVING CONTROL FOR SLACK LENGTH IN STRIPS

William Pechy, Manasquan, N. J., assignor to American Can Company, New York, N. Y., a corporation of New Jersey

Application October 2, 1947, Serial No. 777,415

3 Claims. (Cl. 271—2.3)

1

This invention relates generally to machines for feeding a continuous strip or web of material having a slack length or loop and has particular reference to devices for controlling the length of the loop within certain predetermined limits as the strip is fed.

The invention contemplates the provision of a continuously operated feeding device for feeding strip or web stock, whether metallic or nonmetallic material, into a free or slack length to form a loop thereof and for advancing the strip intermittently from the loop into a work performing station, the length of material within such a loop being controlled by a suitable mechanism to keep any change in the size of the loop within certain predetermined limits so that the length of material in the loop remains substantially the same.

An object of the invention is the provision in a machine for feeding a continuous strip or web of material having a free length or slack loop, of a control mechanism wherein the size of the loop is controlled for maintaining substantially constant the length of material in the loop.

Another object is the provision of such a control mechanism wherein the length of material in the loop is replenished in accordance with the feeding of the material from the loop.

Another object is the provision in such a control mechanism of variable speed feeding devices for the web wherein the material in the loop, as the loop varies in size within predetermined limits, effects a change in the rate of feeding of the web into the loop for maintaining a predetermined length of material in the loop during operation of the machine.

Numerous other objects and advantages of the invention will be apparent as it is better understood from the following description, which, taken in connection with the accompanying drawings, discloses a preferred embodiment thereof.

Referring to the drawings:

Figure 1 is a side elevational view of a machine embodying the present invention with parts broken away and parts in section, the view also including a wiring diagram of electrical apparatus utilized in the operation of the machine;

Fig. 2 is a fragmentary view of a control mechanism as taken substantially along the line 2—2 in Fig. 1;

Fig. 3 is a plan sectional view of the machine shown in Fig. 1 taken substantially along the broken lines 3—3 in Fig. 1;

Fig. 4 is an enlarged sectional view of a contin-

uously operated feeding device as taken substantially along the line 4—4 in Fig. 1;

Fig. 5 is an enlarged sectional view of an intermittently operated feeding device as taken substantially along the broken lines 5—5 in Fig. 1; and

Fig. 6 is a sectional detail of a free-wheeling device, the view being taken substantially along the line 6—6 in Fig. 5.

As an exemplary embodiment of the present invention the drawings illustrate a feeding mechanism for advancing a continuous strip or web A of metallic or nonmetallic material and for controlling the size of a loop of the material moving between two different feeding devices in the mechanism. The material or stock A (Fig. 1) is unwound from a reel B and fed upwardly into a loop C by a primary or continuous feeding device D. The material A is fed or withdrawn from the loop C by a secondary or intermittently operated feeding device E which feeds the stock into a punch press F or other machine for punching and forming articles therefrom.

The size of the loop C is controlled to keep it between upper and lower or maximum and minimum limits as indicated by the dot and dash lines G and H. For this purpose a control mechanism I is provided for effecting a change in the rate of feeding of the material into the loop C in accordance with a change in the size of the loop. This keeps the size of the loop between the limits as indicated by G and H and thus maintains substantially constant the free or slack length of the material within the loop.

The reel B is mounted on a cross bar 11 which is journaled in slide blocks 12 carried in slots 13 of a reel frame 14 (Figs. 1 and 3). The frame 14 may be secured to a machine base or directly to the floor adjacent the press or other machine F. The reel B is supported on rollers 15 which are rotatably carried in the frame 14.

The material A is unwound from the reel and is drawn or fed upwardly by a pair of rotating feed rolls 16, 17 of the primary feeding device D which is located above the reel B (Figs. 1 and 4). Feed rolls 16, 17 are secured respectively to spaced horizontal shafts 18, 19 which are journaled in suitable bearings in a bracket 21. Shaft 18 is extended at one end and is driven by a sprocket 22 which is secured to this shaft. A drive gear 23 also is secured to the shaft 18 and this gear meshes with and drives a gear 24 secured to the shaft 19 for effecting the rotation of the feed rolls 16, 17 in unison and in opposite directions.

The bracket 21 is secured to a pair of spaced and parallel vertical supports or pipes 25 (Figs. 1 and 3) adjacent the lower or entrance end of a vertically disposed ascending chute 26 through which the web material A is fed. Chute 26 is secured to the pipes 25 by a pair of brackets 27. The pipes 25 together with vertical supports or pipes 28 and connecting cross pipes 29 comprise the frame of the mechanism. Pipes 25 are secured at their lower ends in pipe fittings 31 fastened to the floor or base of the mechanism and the pipes 28 are secured at their lower ends in bosses 32 formed on the frame of the press or other machine F.

The rollers 16, 17 of the primary feeding device D are driven continuously by an endless chain 33 which passes over the sprocket 22 and a sprocket or driven clutch element 34 carried on one end of a crank shaft 35 of the press F which provides the actuating or driving means (Figs. 1, 3 and 5). Shaft 35 is the main shaft of the press and may be driven in any suitable manner.

The sprocket 34 is formed with a stepped or shouldered bore 36 (Figs. 5 and 6) within which a free-wheeling clutch member or drive collar 37 is located. The drive collar 37 is secured to the shaft 35 and cooperates with the sprocket or driven clutch element 34 in providing a driving clutch 38 for the feeding device D. The outer periphery of the clutch member or drive collar is formed with a plurality of spaced wedge-shaped recesses 39, in each of which a cylindrical element or gripping roller 41 is located. During the operation of the press F, the collar 37 rotates in a clockwise direction as illustrated in Fig. 6, and thereby wedges the gripping rollers 41 between the sloping surfaces of the recesses and the bore 36 to effect continuous operation of the primary feeding device D.

As the web of material A moves upward from the feeding device D through the ascending chute 26, it passes out of an opening 42 in the side of the chute to form the loop C (Fig. 1). Such a loop extends across a predetermined space and gradually curves downwardly into an opening 43 in the side of a vertically disposed descending chute 44. This latter chute is secured by a pair of spaced brackets 45 fastened to the pipes 28.

The web of material A is fed down and out at the bottom end of the descending chute 44 by the secondary or intermittently operated feeding device E located beneath the chute for feeding the web into a die 46 of the press F (Fig. 1). Such a device operates in time with the operation of the press in order to feed a steady supply of the stock A thereto.

The secondary feeding device E includes a pair of spaced feed rolls 47, 48 between which the web of material A passes (Figs. 1, 3 and 5). The feed rolls 47, 48 are secured respectively to spaced longitudinal shafts 51, 52 which are journaled in suitable bearings in a bracket 53 which is integral with a plate 55 secured to the press F.

The shaft 51 is extended at one end and is journaled in a suitable bearing in an extension 54 of the bracket 53. This shaft is driven by a ratchet wheel 56 which is secured to its outer end. A drive gear 57 also is secured to the shaft 51, and meshes with and drives a gear 58 secured to the shaft 52 for effecting the rotation of the feed rolls 47, 48 in unison and in opposite directions.

The rollers 47, 48 of the secondary feeding device E are operated intermittently by a pawl 61 which engages with teeth 62 formed on the ratchet wheel 56. The pawl 61 is pivotally carried on an

arm 63 of a bell crank 64 which is free to rock on a stud 65 secured to the end of the shaft 51 (Figs. 1, 3 and 5).

The bell crank 64 is actuated by a link 66 which is pivotally connected at one end to an arm 67 of this crank. The opposite end of the link 66 is pivotally and eccentrically mounted on a disc 68 secured to an end of the crank shaft 35 of the press F (Figs. 1, 3 and 5). The crank shaft 35 thus serves as a single actuating or driving means for both the primary feeding device D and the secondary feeding device E.

For best results, the secondary feeding device E normally operates at a slightly faster rate of speed than the primary feeding device D and therefore feeds the web material A from the loop faster than the material is fed into the loop. Thus, as the operation of the press F continues, the size of the loop gradually decreases from its normal size indicated by the letter C to that illustrated by the loop H, having an insufficient amount of material, at its lower limit.

Upon the loop reaching the lower limit H, the web of material in the loop engages against a lever 71 connected to a normally open switch 72 of the control mechanism I (Figs. 1 and 2). The moving web A actuates the lever 71 and closes the switch 72 and thereby establishes an electric circuit which starts a normally idle electric motor 73 which serves as an auxiliary actuating or driving means for the feeding device D. This auxiliary drive increases the rate of feeding of material A into the loop beyond the rate that it is being withdrawn by the device E so as to replenish or build up a reserve of the material in the loop and thus increase the size of the latter.

The motor 73 is mounted on a bracket 74 secured to the frame 14 (Fig. 1). An endless belt 75 passes over a motor sheave 76 and a sheave 76 formed on the driven clutch element or sprocket 34 (Figs. 5 and 6). The motor when in operation increases the rotative speed of the sprocket 34 beyond the normal speed of the shaft 35 so that the sprocket rotates on this shaft. This allows the gripping rollers 41 to drop back into the recesses 39 and disengage the sprocket 34 from its driving connection with the clutch member 37. The driving clutch 38 thereupon ceases to function in clutched connection with the crank shaft 35 and in effect provides a free-wheeling device for the sprocket 34 for independently driving the primary feeding device D.

The motor 73 continues to operate and drive the primary feeding device D, gradually increasing the length of web or material A in the loop until the size of the latter reaches its upper limit as illustrated by the dot and dash loop G. The advancing web A then engages and actuates a lever 77 which is pivotally connected to a normally closed switch 78 of the control mechanism I to effect opening of this switch.

Opening of the switch 78 breaks the electric circuit connecting with the motor 73 and thus stops the motor. Thus the auxiliary drive ceases to operate. The primary feeding device D thereafter is driven through the driving clutch 38 from the shaft 35 as previously described and the web of material is fed at its normal rate. In this manner the size of the loop C is maintained within the upper and lower limits G, H through the action of the switches 72, 78 of the control mechanism.

The control mechanism I includes a pair of spaced guides 81 (Figs. 1 and 2) which are vertically disposed and welded to the cross pipes

29 on each side of the path of the moving web of material A forming the loop, so that the latter may pass freely therebetween. The guides are held in spaced relation by rods 82 bolted between their upper and lower ends. The switches 72, 78 are mounted on the side of one of the guides 81 with the levers 71, 77 extending into the path of the advancing loop of material A.

Reference should now be had to the wiring diagram in Fig. 1 which includes a starting circuit J and a holding circuit K. The starting circuit J includes the switch 72 and a normally open relay switch 83 which is actuated by a normally de-energized solenoid 84. In this circuit one side of the switch 72 is connected by a wire 85 to the electric motor 73. The other side of the switch is connected by a wire 86 to the solenoid 84. The solenoid is also connected by a wire 87 to a suitable source of electric current such as a generator 88. The other side of the generator is connected by a wire 89 to the motor 73.

Hence when the switch 72 is closed, the starting circuit J is completed and electric current from the generator 88 passes along this circuit and excites the motor 73 and also energizes the solenoid 84. Energizing of the solenoid closes the relay switch 83 and thereby establishes the holding circuit K.

The holding circuit K includes the relay switch 83 and the normally closed switch 78. In this circuit one side of the switch 78 is connected by a wire 91 to the wire 85 of the starting circuit J. The other side of the switch is connected by a wire 92 to the relay switch 83. The relay switch is also connected by a wire 93 to the wire 86 of the starting circuit J.

Hence upon establishment of the starting circuit J, electric current from the generator 88 flows from the wire 85, along the wire 91, through the closed switch 78, wire 92, closed relay switch 83, wires 93, 86, solenoid 84, and returns to the generator along the wire 87. Current passing along this circuit maintains the solenoid 84 in an energized condition and thus keeps the motor 73 operating after the loop C of material has been increased sufficiently to ride off the lever 71 and thereby permit the switch 72 to open.

Operation of the motor 73 continues, through the flow of electric current along the combined starting circuit J and holding circuit K, until the loop increases sufficiently to engage and actuate the lever 71. Actuation of the lever opens the switch 78 and this breaks the combined starting and holding circuits J and K. The flow of current thereby ceases and the motor 73 thus stops operating and thus permits further feeding of the material at the reduced rate of speed under the operation of the press crank shaft as hereinbefore explained. This breaking of the circuits also de-energizes the solenoid 84 and thereby opens the relay switch 83, thus resetting the circuits for a repeat operation when the loop C again decreases in size to its lower limit H as hereinbefore explained.

While strip or web material has been described herein the invention is of course applicable to the control of loops of other material for example the material to be fed and operated upon might be wire material. Any material which can be fed and controlled by the present invention is intended to be included.

It is thought that the invention and many of its attendant advantages will be understood from the foregoing description, and it will be apparent that various changes may be made in the form, 70

5 construction and arrangement of the parts without departing from the spirit and scope of the invention or sacrificing all of its material advantages, the form hereinbefore described being merely a preferred embodiment thereof.

I claim:

1. In a machine for feeding strip, web or similar material along a path of travel, the combination of primary feeding devices for continuously advancing the material into a slack loop, secondary feeding devices for intermittently feeding the material from said loop, actuating means including a shaft for operating said secondary feeding devices, a drive clutch mounted on said actuating shaft and including a rotating driven element having a clutch connection with the shaft for operating said primary feeding devices, auxiliary actuating means connecting with the driven element of said clutch for rotating said element relative to said actuating shaft to change the rate of advancement of the strip by said primary feeding devices, and control means connecting with said auxiliary actuating means and operable by a predetermined amount of material in 10 said slack loop for engaging or disengaging said driven clutch element and said drive shaft to regulate the length of material in said loop in accordance with the feeding of the material from the loop.
2. In a machine for feeding strip, web or similar material along a path of travel, the combination of primary feeding devices for continuously advancing the material into a slack loop, secondary feeding devices for intermittently feeding the material from said loop, actuating means including a shaft for operating said secondary feeding devices, a drive clutch mounted on said actuating shaft and including a rotating driven element having a clutch connection with the 15 shaft for operating said primary feeding devices, auxiliary actuating means connecting with the driven element of said clutch for rotating said element relative to said actuating shaft to change the rate of advancement of the strip by said primary feeding devices, and control means connecting with said auxiliary actuating means and operable by a predetermined amount of material in 20 said slack loop for engaging or disengaging said driven clutch element and said drive shaft to regulate the length of material in said loop in accordance with the feeding of the material from the loop.
3. In a machine for feeding strip, web or similar material along a path of travel, the combination of primary feeding devices for continuously advancing the material into a slack loop, secondary feeding devices for intermittently feeding the material from said loop, actuating means including a shaft for operating said secondary feeding devices, a drive clutch mounted on said actuating shaft and including a rotating driven element having a clutch connection with the 25 shaft for operating said primary feeding devices, auxiliary actuating means connecting with the driven element of said clutch for rotating said element faster than said actuating shaft to increase the rate of advancement of the strip by said primary feeding devices, and control means connecting with said auxiliary actuating means and operable by a predetermined amount of material in 30 said slack loop for engaging or disengaging said driven clutch element and said drive shaft to regulate the length of material in said loop in accordance with the feeding of the material from the loop.
4. In a machine for feeding strip, web or similar material along a path of travel, the combination of primary feeding devices for continuously advancing the material into a slack loop, secondary feeding devices for intermittently feeding the material from said loop, actuating means including a shaft for operating said secondary feeding devices, a drive clutch mounted on said actuating shaft and including a rotating driven element having a clutch connection with the 35 shaft for operating said primary feeding devices, auxiliary actuating means connecting with the driven element of said clutch for rotating said element faster than said actuating shaft to increase the rate of advancement of the strip by said primary feeding devices, and control means connecting with said auxiliary actuating means and operable by a predetermined amount of material in 40 said slack loop for engaging or disengaging said driven clutch element and said drive shaft to regulate the length of material in said loop in accordance with the feeding of the material from the loop.
5. In a machine for feeding strip, web or similar material along a path of travel, the combination of primary feeding devices for continuously advancing the material into a slack loop, secondary feeding devices for intermittently feeding the material from said loop, actuating means including a shaft for operating said secondary feeding devices, a drive clutch mounted on said actuating shaft and including a rotating driven element having a clutch connection with the 45 shaft for operating said primary feeding devices, auxiliary actuating means connecting with the driven element of said clutch for rotating said element faster than said actuating shaft to increase the rate of advancement of the strip by said primary feeding devices, and control means connecting with said auxiliary actuating means and operable by a predetermined amount of material in 50 said slack loop for engaging or disengaging said driven clutch element and said drive shaft to regulate the length of material in said loop in accordance with the feeding of the material from the loop.
6. In a machine for feeding strip, web or similar material along a path of travel, the combination of primary feeding devices for continuously advancing the material into a slack loop, secondary feeding devices for intermittently feeding the material from said loop, actuating means including a shaft for operating said secondary feeding devices, a drive clutch mounted on said actuating shaft and including a rotating driven element having a clutch connection with the 55 shaft for operating said primary feeding devices, auxiliary actuating means connecting with the driven element of said clutch for rotating said element faster than said actuating shaft to increase the rate of advancement of the strip by said primary feeding devices, and control means connecting with said auxiliary actuating means and operable by a predetermined amount of material in said slack loop for engaging or disengaging said driven clutch element and said drive shaft to regulate the length of material in 60 said loop in accordance with the feeding of the material from the loop.
7. In a machine for feeding strip, web or similar material along a path of travel, the combination of primary feeding devices for continuously advancing the material into a slack loop, secondary feeding devices for intermittently feeding the material from said loop, actuating means including a shaft for operating said secondary feeding devices, a drive clutch mounted on said actuating shaft and including a rotating driven element having a clutch connection with the 65 shaft for operating said primary feeding devices, auxiliary actuating means connecting with the driven element of said clutch for rotating said element faster than said actuating shaft to increase the rate of advancement of the strip by said primary feeding devices, and control means connecting with said auxiliary actuating means and operable by a predetermined amount of material in said slack loop for engaging or disengaging said driven clutch element and said drive shaft to regulate the length of material in 70 said loop in accordance with the feeding of the material from the loop.

ated by the strip having a minimum amount of material in said slack loop for effecting rotation of said driven clutch element through said auxiliary actuating means and the other of said switches being engaged by the strip having a maximum amount of material in said slack loop for effecting clutch connection between said shaft and said driven clutch element.
